PRINTING PRESS GRIPPER MECHANISM

Emory W. Worthington, Chicago, Ill., assignor to
The Goss Printing Press Company, Chicago, Ill.,
a corporation of Illinois

Application February 18, 1943, Serial No. 476,261

4 Claims. (Cl. 101—409)

The present invention relates to new and useful improvements in sheet gripping devices, and more particularly to improved spring grippers or folding jaws especially adapted for use in printing presses.

Objects and advantages of the invention will be set forth in part hereafter, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates embodiments of the invention, and, together with the description, serve to explain the principles of the invention.

Fig. 1 is a fragmentary vertical section through a cylinder to which the improved gripper is applied as embodied in one form of the invention.

Fig. 2 is a view showing a modified construction of the shaft and gripping finger of the type illustrated in Fig. 1.

Fig. 3 is a view similar to Fig. 1, showing another embodiment of the invention.

Fig. 4 is a view similar to Fig. 2, showing a modification in the construction of the shaft and gripping finger of the type illustrated in Fig. 3.

The invention is directed to providing novel and improved sheet gripping instrumentalities, operating by a gripping or clamping action, either medianly or on the edge, of a sheet or group of sheets, as in feeding or folding; and in its main features being capacitated for use either in a gripping finger mechanism or a folding jaw mechanism.

The invention is particularly directed to providing improvements in gripper mechanisms of that type in which the gripper mechanism is mounted on a cylinder having a slot in its periphery one side wall of which is formed or provided with one or more gripping members, jaws or surfaces for coaction with one or more gripping or clamping members or jaws mounted on a shaft rocked through a small angle by cam mechanism or the like carried by the cylinder to effect the opening and closing of the gripper mechanism.

In prior patents, No. 1,843,754, dated February 2, 1932, and No. 1,895,124, dated January 24, 1933, the latter reissued May 28, 1935, under Re-issue No. 19,591, there are disclosed gripper mechanisms of this type in which single leaf

spring and laminated leaf spring grippers are provided for coaction with a stationary gripper or grippers formed or provided upon one of the walls of the slot in the cylinder. Such gripper mechanisms, particularly when equipped with laminated leaf spring grippers, have been found highly efficient for use in sheet transfer gripping and folding operations because of their elastic gripping actions, great durability, capability of firmly gripping commodities of different thicknesses, and in enabling high speed folding operations to be carried out.

Gripper mechanisms of this type, however, while highly efficient, as stated, are open to certain inherent practical objections, particularly in their use on small cylinders and when operated by cam mechanisms of a certain kind, which are otherwise structurally desirable. It has been found, for example, that in the mounting of the resilient grippers on an actuating rock shaft operated by cams inclosed in the wheel, shock vibrations are caused which are transmitted to and tend to cause jumping of the cams and undue wear and tear on the cam roller surfaces. Another objection to this prior type of gripper mechanism is that the length of the resilient grippers, the radius of action of the moving grippers and the diameter of the cam path cannot be readily designed and regulated to suit different conditions of service or different sizes of cylinders. Furthermore, in the use of resilient grippers on the shaft the formation of indentations, corrugations and the like in the gripped sheets, when desired, cannot be readily made.

The present invention has for its main object

the provision of a novel gripper mechanism which

overcomes these and other minor objections to

gripper mechanisms of the aforesaid prior type

and which possesses other substantial and im-

portant advantages.

In its structural organization the present invention provides a gripper mechanism in which the stationary grippers are in the form of laminated leaf spring members mounted on the cylinder, and in which the movable grippers are in the form of non-resilient fingers solidly mounted on the actuating shaft, whereby all vibratory shock strains are sustained by the cylinder and damped by the mounting of the resilient grippers thereon and such strains prevented from falling on the shaft and being transmitted to the cam mechanism.

The present invention also provides a novel construction, mode of mounting and arrangement of the resilient gripping members and grip-

ping fingers whereby the other disadvantages of the prior type of gripper mechanism referred to are effectually overcome and additional advantages secured.

Referring now more particularly to the embodiment of the invention shown in Fig. 1, 10 indicates a portion of a cylinder structure which is provided with a radial slot 11 opening through its rim and with a recess 12 also opening through its rim and communicating with the slot at one side thereof. This recess has an inclined bottom seat wall 13 extending between the slot and periphery of the rim and tangentially to the latter. Suitably secured in the recess and closing the same except at its side intersecting the slot is a recess closing and gripper supporting block 14. The block 14 is shaped at its base to conform to the seat wall 13 on which it rests and at its outer surface to conform to the curvature of the outer surface of the cylinder.

The side of the block which faces the slot 11 terminates short thereof and lies adjacent thereto but within the recess. Said side of the block has an outer face 15 and an inwardly projecting shoulder 16 at the base thereof, the face 15 and inner face of the shoulder being disposed in parallel planes and both inclined outwardly toward the periphery of the cylinder at an angle thereto and to the slot 11. Mounted on the block is a laminated leaf spring gripping member 17 having an inner end or butt portion 18 abutting against the seat face 13 and shoulder 16 and having an outer free end portion whose tip 19 constitutes a gripping jaw. A clamp plate 20 bears on the relatively outer face of this gripping member and a machine bolt 21 passes therethrough and through the gripping member and into the shoulder and clamps the inner end or butt portion of said member against the shoulder 16.

The plate 20 bears at its inner end on the seat face and free portion of the member 17 outwardly beyond the shoulder 16, but is of less length than the member 17 and terminates short of the outer end thereof, leaving the latter projecting to form the jaw 19 which is located adjacent to the periphery of the cylinder and exposed to the slot through the adjacent side of the recess. The free portion of the spring member 17 is backed and limited in its movement toward the slot, but is free to yield into the space between it and the face 15 of the block 14. Preferably the free portion of the spring member 17 is pre-loaded or placed under initial spring tension, as by forming the plate 20 with a recess 22 and a projecting portion 23 holding the member slightly flexed so that it will give an instantaneous preliminary pressure on the gripped sheet immediately the gripper 19 engages the sheet.

A plurality of such leaf spring grippers 17 may be mounted side by side or at spaced intervals on the cylinder and a movable non-resilient gripper 24 is provided on a rock shaft 25 for co-action with each gripper 17. The shaft 25 is mounted on the cylinder within the slot 11. The shaft is adapted to be periodically rocked through a small angle, in the usual manner, by any standard, well known or other suitable mechanism (not shown) mounted within the cylinder so as to move the grippers 24 toward and from the grippers 17. Each group of these grippers 24, as shown in Fig. 1, comprises a gripping finger 26 having a gripping jaw 27 and secured by a split hub 28 and a machine bolt or screw 29, to the shaft, so that it will be firmly and solidly mounted on the shaft. The jaw 27 is adapted when rocked

toward the member 17 to grip an inserted sheet or sheets 31 between it and the jaw 19 of the member 17 and when rocked away from the member 17 to effect the release of the sheet in an obvious manner.

It will be observed that the inclination of the gripper 17 and movement of the gripper 24 is such that the jaws 19 and 27 when in gripping position will be parallel with each other and grip the sheet in a plane parallel with the slot 11 so that the sheet will be quickly and firmly gripped in a vise-like manner and quickly released through small movements of the gripper 24, allowing the action to be very rapidly carried out. Another advantage incident to the described mounting of the gripper 17 is that its vibrations are damped and sustained by the cylinder which absorbs them so that no shocks are transmitted to the shaft or its operating cam mechanism to cause injury to or undue wear and tear on the latter. The gripping mechanism may, therefore, be used in high speed actions without the production of dynamic and vibration effects liable to damage any of the parts of the apparatus. Furthermore, the novel arrangement and mode of mounting the resilient grippers permits of the use of grippers of a length best suited for any sized cylinder and without requiring different arrangements of parts in different sizes of cylinders. The invention also provides for the use of sturdy non-resilient gripping fingers on the shaft, solidly mounted thereon and fingers having a smaller radius of action than would otherwise be the case, which allows greater speed of action and further reduces friction and wear on the parts. By the use of these fingers desired indentations, corrugations and the like may be more readily made in even thick sheets of material during the gripping action and such fingers assist in preventing torsional deflection or springing and the transmission of shocks, jars and vibrations to the shaft and its cam operating mechanism.

It is possible with this novel construction of gripping mechanism to use an assembly of the resilient grippers and mount the same as a unit or in a plurality of sections entirely across the cylinder, thus doing away with the previous troublesome practice of mounting individual resilient grippers in spaced relation on the rock shaft and the necessity of adjusting them and keeping them adjusted. Such an assembly may be applied and removed for replacements, repairs and other purposes without the necessity, as heretofore, of dismantling the rock shaft and parts thereon, and with a great saving of time and labor in effecting these operations.

By providing gripping fingers of the type disclosed it is also possible to machine the grippers and shaft in a single piece so as to allow a very strong section in the gripping members. Such a construction is disclosed in Fig. 2 in which the shaft 25' is shown as provided with a gripper 24' formed integrally therewith.

In the embodiment of the invention shown in Fig. 3 a gripping mechanism is provided which has the same general advantages as that shown in Fig. 1, but which structurally varies therefrom in certain particulars and grips the sheet in a different manner. As shown, the cylinder 10' shown in Fig. 2 is formed with a radial slot 11' opening through its periphery and with a recess 12' also opening through its periphery and into one side of the slot. This recess extends lengthwise circumferentially of the cylinder and

at its end remote from the slot is formed with an inclined seat wall or face 13' and a shoulder 13", said seat wall being inclined at an obtuse angle to the slot and on a line tangential to the periphery of the cylinder. A laminated leaf spring gripping member 17' has its butt portion 18' bearing on the face 13' and against the shoulder 13" and is clamped against the former by a closure and clamp block 14' fastened with the gripping member to the cylinder by a machine bolt or screw 21'. The block 14' has an inner end face conforming to the shoulder 13" and an outer curved face conforming to the curvature of the periphery of the cylinder and is of less length than the gripper 17' so as to close the portion of the recess beyond the gripper between the shoulder 13" and free end 19' of the gripper, leaving said gripper end 19' exposed to the slot 11' at the inner end of the recess and at the surface of the cylinder adjacent thereto. The inner face of the block is formed with a recess 22' and a projection 23' to preload the spring or to hold it under initial tension. The gripper 17' thus extends from its butt end at an angle toward the periphery of the cylinder and in one direction circumferentially of the cylinder with its free end or jaw portion 19' disposed in a plane coincident with that of the adjacent portion of the surface of the cylinder and circumferentially thereof.

Mounted in the slot 14' is a rock shaft 25', similar to the shaft 25, on which is mounted a non-resilient gripper 24' having a gripping finger 26' terminating in a gripping jaw 27' and secured to the shaft by a split hub 28' and machine bolt or screw 29'. The finger 26', as shown, extends outward in the slot beyond the shaft and its jaw 27' lies just beyond the surface of the cylinder and projects in the opposite direction to and normally overlies the jaw 19' of the gripper 17'. The action of the parts in this embodiment is the same as that of the embodiment disclosed in Fig. 1 except that the sheet 30' fed to the jaws 19' 27' in the direction of rotation of the cylinder is clamped flatly and in a vise-like manner between a resilient jaw and a non-resilient jaw at the surface of the cylinder on a line substantially flush with such surface. As in the structure disclosed in Fig. 1, the resilient gripper is mounted on the cylinder which sustains and dampens all vibration shocks and coacts with a solid non-resilient gripper on the actuating rock shaft which resists torque strains and prevents transmission of vibration shocks to the shaft and through the shaft to its actuating cam mechanism.

Grippers of the type employed in Fig. 3 may be formed integral with the shaft, as shown by the gripper 24" and shaft 25" in Fig. 4, in the same manner as that explained with reference to Fig. 2.

The invention in its broader aspects is not limited to the specific mechanisms shown and described, but departures may be made therefrom within the scope of the appended claims without departing from the principles of the invention and without sacrificing its chief advantages.

Having thus described my invention, I claim:

1. A gripping mechanism including in combination a cylinder having a radial slot opening through its periphery and a recess at one side of said slot, a preloaded laminated spring gripping member having relatively stiff and flexible butt and gripping jaw ends, fastening means including a block closing the recess except at its side facing the slot and securing the butt end of

said gripping member to the cylinder and leaving its jaw end free and at an angle to the slot and so as to be pressed to a gripping position substantially parallel with the slot, a rock shaft in the slot, and a non-resilient gripping finger mounted on the shaft for movement toward and from the gripping member and having a jaw arranged to clamp an inserted sheet against the gripping jaw of said member in a direction radially of the cylinder.

2. A gripping mechanism including in combination a cylinder having a radial slot opening through its periphery and a recess at one side of said slot, a laminated spring gripping member having relatively stiff and flexible butt and gripping jaw ends, fastening means including a block closing a portion of the recess circumferentially of the cylinder beyond said side of the slot so as to leave a portion of the recess open at its side facing the slot and securing the butt end of said gripping member within the recess with its free end disposed at an angle to the radial line of the slot and so as to adapt it to be pressed in the direction of the recess to a gripping position, a rock shaft mounted in the slot, and a non-resilient gripping member mounted on the shaft for cooperation with the resilient gripping member and having a finger extending outwardly toward the circumference of the cylinder and terminating in a gripping jaw bent laterally in a direction toward the recess and movable in such direction to clamp an inserted sheet against the gripping jaw of the resilient gripping member.

3. A gripping mechanism including in combination a cylinder having a radial slot opening through its periphery and a recess at one side of said slot, a laminated spring gripping member having relatively stiff and flexible butt and gripping jaw ends, fastening means including a block closing the recess except at its side facing the slot and securing the butt end of said gripping member to the cylinder and leaving its jaw end free and arranged adjacent to the periphery of the cylinder at such an angle to the slot as to adapt it to be pressed to a gripping position within the open side of the recess, a rock shaft in the slot, and a non-resilient gripping finger mounted on the shaft for movement toward and from the spring gripping member and having a jaw operative in one direction of movement to press and tension the spring member and to clamp an inserted sheet against the gripping jaw of said member and operative in its other direction of movement to relieve the spring member from pressure and permit it to return by its resiliency to non-gripping position.

4. A gripping device including in combination a cylinder having a peripheral portion and provided with a dial slot and a recess at one side of the slot, a resilient leaf spring gripping member, fastening means including a block closing a portion of the recess and fixing the spring member at one end to the cylinder leaving its opposite end free and in the form of a gripping jaw normally exposed in the recess at the periphery of the cylinder, a rock shaft mounted within the slot, and a non-resilient gripping finger mounted on the shaft for movement toward and from the spring gripping member and arranged to clamp an inserted sheet against the gripping jaw of said member in the direction of rotation of the cylinder.

EMORY W. WORTHINGTON.
